UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

APPARATUS FOR HEATING AND SOFTENING SHOES AND PARTS THEREOF.

Application filed May 9, 1923. Serial No. 637,891.

This invention relates to apparatus for heating and moistening materials used in manufacture, and more particularly to apparatus for softening shoes and parts thereof in process of manufacture. It is illustrated in a form designed to be used to heat and moisten the vamp and toe stiffener of an assembled shoe to facilitate the pulling-over operation and to render the materials soft and pliant so that they may be readily manipulated and shaped.

An object of the invention is to provide an improved organization of the type comprising vaporizing means and means for supplying water to be vaporized thereby, and in which organization there shall be adequate provision for taking care of overflow in case the operator neglects to shut off the supply of water when the apparatus is not in use or permits the water to be supplied too copiously while the apparatus is in use.

A feature of the invention consists in a novel construction of the vaporizing element by which the overflow, if there be any, will be discharged at a point or points where it will not wet the lasts or the uppers associated therewith. Another feature related thereto consists in providing a tank to receive the overflow.

When, as in the illustrated design, the quantity of water to be supplied to the vaporizing element is limited by a supply tank, a feature of the invention consists in proportioning the supply tank and the overflow tank so that the latter will hold as much water as the former can supply at one filling, and thus guard against flooding the bench or floor.

Still another feature consists in forming the base of the apparatus to provide the aforesaid overflow tank, in which respect the utility of the base is increased to good advantage.

Another object of the invention is to conserve the heat in the vaporizing element as much as possible by restricting its means of escape by conduction. For practical reasons it is desirable to make the base and the vaporizing element of cast iron and to mount the vaporizing element directly on the base.

Such mounting would ordinarily involve considerable aerial contact of the two cast iron elements such that the heat developed in the vaporizing element would have considerable opportunity to be dissipated by conduction to the base. A feature of the invention which guards against such heat loss consists in providing the base and the vaporizing element with contacting portions which support the latter and restrict the actual contact to a negligible aggregate area and yet afford a firm mounting. Moreover, these portions are preferably formed to provide an anti-slip mounting. Again, if the vaporizing element is connected to the base to fasten it positively against displacement the connecting means may also be designed to minimize conduction of heat, and for this purpose the illustrated construction includes two connecting elements each so long and yet so restricted in cross sectional area that their capacity to conduct heat from the vaporizer to the base is negligible.

The features above described are specially advantageous in an apparatus that utilizes electricity as the heating medium, and the illustrated apparatus is, in fact, designed to utilize electric heating means. It is necessary, however, to guard against wetting the electrical equipment, and accordingly a further feature of the invention consists in improved means for protecting the electric elements from being wet by careless handling of the water used in the apparatus.

Other features of the invention are hereinafter described and claimed and are illustrated by the accompanying drawings.

Referring to the drawings:

Fig. 1 is a front elevation of a heating and softening apparatus embodying the invention in a preferred form;

Fig. 2 is an end elevation thereof partly in section and including an assembled shoe in position for treatment; and

Fig. 3 is a sectional view on a larger scale of the structure intersected by the line 3—3 of Fig. 1.

The apparatus comprises three principal cast iron units, viz., a supporting base 10, a heat radiator 11, and a water tank 12. The bottom of the base 10 is provided with bosses

13 which, if the apparatus is to be installed on a bench, may rest on the bench, but if it is desired to stand the apparatus on the floor the bosses may be bored and tapped to receive legs such as pipes 14. For reasons hereinafter explained the base 10 preferably embodies the form of a pan or basin to hold water.

The width of the base 10 and heat radiator 11 is preferably sufficient to accommodate a series of four or more shoes arranged side by side, although a capacity for four shoes is usually sufficient. As shown by Fig. 1, the heat radiator 11 is shaped like the span of a bridge, having two bosses 15 at each end to provide pedestals by which it may stand on any suitable supporting means. In the illustrated design the base 10 is provided with supporting bosses 16 arranged to register with the bosses 15. These bosses, which operate with each other in pairs, are the only portions that afford contact of the radiator with the base, and they are preferably formed to restrict the areas of contact to mere points to minimize the transmission of heat. For this reason the contacting portions of the bosses are preferably beveled to sharp edges 15' and 16' which are arranged to cross one another and therefore touch only at the points of intersection. This construction affords a considerable range of horizontal adjustment of the radiator relatively to the base to permit binding screws 17 extending downwardly through holes in the radiator to register with tapped holes in the base. Two binding screws are sufficient, and they are preferably long and slender to minimize conduction of heat, and arranged one at each side of the apparatus as shown by Fig. 1 and 46 between the pairs of contacting bosses as shown by Fig. 2. When the binding screws are set up tightly the crossed edges of the bosses hold the radiator securely against lateral displacement, thereby relieving the 45 binding screws from lateral stresses.

The forward portion of the base 10 is provided with a platform 18 which may be made of wood and which serves as a support for the lasts of the assembled shoes. The forward portion of the radiator 11 overhangs the platform 18 but is far enough above the latter to provide a space for the reception of the toe ends of the lasts, and yet low enough to permit the vamps of the assembled shoes to overlie it. The heat radiator is thus adapted to intervene between the lasts and the vamps to administer treatment to the latter without moistening or appreciably heating the lasts. For the purpose of supporting the platform so that it may be readily removed the sides of the base 10 are provided with ledges 19 as shown by Fig. 1. A guard consisting of a bar 20 of heat-insulating material such as wood is preferably fastened to the forward edge of the radiator 11, partly

to prevent the lasts from striking the radiator, partly to prevent the lasts, by engagement with their instep portions, from being thrust too far to the rear, and partly to prevent the overlying portions of the vamps from touching the hot iron of the radiator.

The water tank 12 is supported by two upright rods 21, the base 10 being provided with sockets 22 to receive the lower ends of the rods and the water tank being provided with sockets 23 to receive the upper ends. The tank may be lifted from the rods whenever necessary to make repairs or to dismantle the apparatus for any other purpose. A discharge pipe 24 is screwed into the bottom of the water tank and is provided with a valve 25 to regulate the discharge of water and to shut off the supply when the apparatus is not being used. The discharged water drops through a funnel 26 fastened to a brass plate 27 that forms the top of a vaporizing chamber 28. The cast iron body of the radiator is dished to form said chamber. As the water drops from the funnel it flows over the hot surface 29 of the cast iron body 11 and is immediately converted into vapor under the brass plate 27. By reason of its expansion the vapor spreads laterally throughout the chamber 28 and escapes through many small perforations 30 formed in the plate. A sheet of wire fabric 31 is preferably arranged on the upper surface of the brass plate to prevent the vamps from touching the plate. The vapor that escapes from the perforations 30 is therefore given sufficient opportunity to become distributed laterally before it reaches the work, instead of being concentrated at points in register with the perforations. Consequently the only parts of the apparatus touched by the vamps are the guard 20 and the wire fabric 31. The cast iron body of the heat radiator is preferably provided with many thin ribs or flanges 32 extending upwardly from the surface 29 and touching the bottom of the brass plate. These ribs reinforce the plate, transmit heat to it by direct engagement, and expedite the vaporization of the water by reason of their relatively great area of radiating surface in the chamber 28.

Although any preferred means may be provided to heat the element 11 the illustrated apparatus is designed to be heated by electric heating units 33. Since this apparatus is designed to have a capacity for four shoes at one time it is provided with five heating units each of which is embedded in a boss 36 cast on the bottom of the radiator. These bosses are bored horizontally from the rear to provide sockets to receive the units, and are spaced apart a distance equal to the spacing of the shoes. The sources of heat are thus distributed so that each shoe will be between two of them.

The electric wires 37 leading to the units

35 extend through a board or sheet 38 of heat-insulating material (compressed asbestos-board being represented), and the stretches of wire between this board and the 5 radiator are enclosed in metal tubes 39 each serving one pair of wires. As shown by Fig. 3, the sockets containing the heating units 35 are counterbored to receive the tubes 39 which are fitted tightly in the counterbores and held thereby. In case any water 10 is splashed or spilled above the radiator the tubes 39 will prevent it from reaching the wires 37 and the heating units 35. The board 38 and a metallic hood 40 detachably 15 fastened to its rear side, together form a wiring manifold in which the conductors are further enclosed. The hood has a boss 41 through which a flexible electric cord 42 extends to connect the units 35 with a rheostat 20 45 which may be mounted separately on any suitable support.

When the apparatus is controlled and regulated with due care the water supplied to the chamber 28 is vaporized so rapidly that 25 no water accumulates therein, but if the valve 25 is opened too much, or if the operator should neglect to shut the valve when the electric current is turned off, the discharged water would soon overflow the 30 chamber 28 and permit the entire contents of the tank 12 to spill on the bench or on the floor of the work-room were it not for suitable provision for taking care of the overflow. One of the features of this invention 35 consists in means for taking care of such overflow, and in this respect the pan-shaped base 10 serves as a catch-basin to catch the water. The water capacity of the base is equal to if not greater than that of the supply tank 12. To guard against flooding the 40 vaporizing chamber 28 the cast iron body 11 is provided with one or more overflow ports, two being illustrated in Fig. 1. These ports, indicated at 43, are at the rear of the unit 11 and are so far from the spaces occupied by the lasts that the latter will not be wet even 45 when they are in operative position at the time of overflow. Bosses 44 are formed on the surface 29 of the radiator and the overflow ports are formed in them, the receiving 50 ends of the ports being thus located far enough above the level of the surface 29 to insure vaporization of all the water in the chamber 28 under correct conditions of regulation.

The apparatus described herein is capable of administering moisture to the work in two alternative ways both of which are described in my copending application Serial No. 618, 60 374, filed February 10, 1923. For example, when the heat-radiating element 11 is heated to its maximum temperature, as when all the heating units 35 are operating to their full capacity, both the heat-radiating surface 65 29 and the brass plate 27 are maintained at

temperatures above 212 degrees F., although the temperature of the brass plate is never so high as that of the surface 29. Under these conditions vapor generated by the surface 29 rises as vapor through the holes 30 in the 70 brass plate and does not become condensed until it reaches the work. This would be the preferable method of using the apparatus when the work to be treated would not be injured by the maximum temperature or by 75 a relatively copious supply of vapor, and when it is desired to heat and moisten the work as rapidly as possible.

On the other hand, when the character of the upper leather or any other element to be 80 treated is such that it would be preferable to restrict the heat and moisture the temperature of the heat-radiating element could be reduced either by cutting out one or more of the heating units 35 or by means of the rheostat 85 in the box 45 from which the cord or lead wires 42 receive current. However the temperature of the radiating element 11 is regulated, it is possible to reduce its temperature to a degree that will still be above 212 90 degrees while the temperature of the brass plate 27 will be substantially less than 212 degrees. Under these conditions the vapor generated by the surface 29 will be condensed by the plate 27 and the water of condensation will fill the holes 30 and seal them, thereby preventing the initial vapor from reaching the work. To provide for this method of operation the holes 30 are made 95 so small that the quantity of water necessary to seal them will be supported by surface tension. To make the holes readily apparent in Fig. 3 they are exaggerated but in practice they are preferably no larger than, if as large as, the shank of a common 100 pin.

When the apparatus is operating under the conditions last specified a relatively small aggregate quantity of moisture rises 110 from the many small seals or plugs of water held in the holes 30, and these small bodies of water are continuously replenished by the condensation of the vapor that continues to rise from the surface 29. Thus, without altering the adjustment of the water valve 115 25 the quantity as well as the temperature of the moisture administered to the work may be increased or diminished by regulating the temperature of the element 11.

Having thus described my invention, what 120 I claim as new and desire to secure by Letters Patent of the United States is:

1. A shoe-treating apparatus comprising a 125 heat-radiating element adapted to convert water into hot moist vapor, a tank for supplying water to said heat-radiating element, and an overflow tank having a capacity as great as that of said supply tank and arranged to catch any water that overflows said heat-radiating element.

2. A shoe-treating apparatus comprising a base, a heat-radiating element formed and arranged to vaporize water between the last and vamp of an assembled shoe, and a reservoir for water arranged to discharge water on said element, said base being formed as a catch-basin to catch any water that may overflow said element, and said element being formed and arranged to discharge such overflow into said catch-basin at a point or points located to avoid wetting the last. 5
3. A shoe-treating apparatus comprising a base in the form of a catch-basin to hold water, a work-supporting platform arranged to form a cover for said basin and adapted to support the lasts of a series of shoes assembled on the lasts, a heat-radiating element mounted on said base and formed to overhang the toes of the lasts and support the vamps of the shoes, and means to supply water to said element to be vaporized thereby, said element being formed and arranged to discharge any surplus water into said catch-basin at a point or points located to avoid wetting the lasts on said platform. 10
4. A shoe-treating apparatus comprising a heat-radiating element having a shallow dished portion formed and arranged to overhang the toe of the last and underlie the vamp, means for supporting the last, a foraminous sheet arranged to support the vamp above the bottom of said dished portion, and means to supply water to said dished portion, the latter having an overflow duct the receiving end of which is between the levels of said foraminous sheet and the bottom of the dished portion. 15
5. An apparatus for treating parts of boots and shoes, comprising supporting means having top ridges, and a heat-radiator having bottom ridges arranged to cross and rest on said top ridges, the contact between said means and heat-radiator being restricted to negligible areas at the points where said ridges cross one another. 20
6. An apparatus for treating parts of boots and shoes, comprising supporting means and a heat-radiator having a plurality of pairs of contacting portions by which the heat-radiator is supported, the areas of said contacting portions being restricted to points having a negligible aggregate heat-conducting capacity. 25
7. An apparatus for treating parts of boots and shoes, comprising a supporting base having bosses projecting upwardly, a heat-radiator having bottom ridges arranged to bear on said bosses, the contacting portions of said bosses being ridges arranged to cross those of said radiator to restrict their contact to points and to afford lateral adjustment, and means arranged to fasten said heat-radiator to said base. 30
8. An apparatus for treating parts of boots and shoes, comprising supporting
- means and a heat-radiator having anti-slipping contacting portions by which the heat-radiator is supported. 35
9. An apparatus for treating parts of boots and shoes, comprising metallic supporting means and a metallic heat-radiator having anti-slipping contacting portions by which the heat-radiator is supported and by which the areas of contact are restricted to points having a negligible aggregate heat-conducting capacity. 40
10. A shoe-treating apparatus comprising a base, a heat-radiating element mounted thereon and having one or more sockets to receive electric heating units, posts extending upwardly from said base, a water-tank supported by said posts above the level of said heat-radiating element to supply water to the latter, means fastened to said posts to enclose electric conductors leading to said heating units, and tubes extending from said heat-radiating element to said enclosing means to enclose the corresponding portions of the electric conductors. 45
11. A shoe treating apparatus comprising a stationary heat-radiating element having a series of sockets to receive electric units, a stationary manifold to receive the conductors for said units, said manifold having a series of holes corresponding to said sockets, and a series of tubes the ends of which are arranged respectively in telescopic relation to said element and in contiguous relation to said manifold to enclose the conductors. 50
12. A shoe treating apparatus comprising a base, a heat-radiating element mounted thereon and having a series of sockets to receive electric units, a wiring manifold mounted on said base and having holes to receive the conductors for said units, and a series of tubes fastened to said element and protruding from the mouths of said sockets to said manifold to enclose the conductors. 55
13. A treating apparatus comprising means to support one or more assembled shoes in position for treatment, heat-radiating means formed and arranged to vaporize water between the toes of the lasts and the vamps of the shoes, means to supply water to said heat-radiating means, and means to receive surplus water shed by said heat-radiating means. 60
14. A treating apparatus comprising means to support a series of assembled shoes in position for treatment, and a bridge-like heat-radiator formed and arranged to span the toes of the lasts and underlie the vamps of the shoes, said heat-radiator having sockets spaced according to the spacing of the shoes and adapted to enclose heating units. 65
15. A treating apparatus comprising a bridge-like heat-radiator formed and arranged to span the toes of the lasts and underlie the vamps of a series of assembled

shoes and having a series of sockets to receive electric heating units.

16. A treating apparatus comprising a bridge-like heat-radiator having pedestals at its ends to stand on a support and provide a single unobstructed space for the toes of the lasts of a series of assembled shoes arranged on such support, said radiator being

formed to span the toes of the lasts and underlie the vamps of the shoes and having ¹⁰ one or more sockets open at the rear to receive and enclose heating units.

In testimony whereof I have signed my name to this specification.

FREDERICK M. FURBER.
